UNITED STATES PATENT OFFICE.

ANDREW B. CAMDEN, OF DURANT, OKLAHOMA, ASSIGNOR, BY MESNE ASSIGNMENTS,
OF ONE-HALF TO ELIZABETH M. SCOTT, OF DURANT, OKLAHOMA.

TOOL FOR TREATING RAZOR STROPS.

Application filed October 16, 1922. Serial No. 595,021.

To all whom it may concern:

Be it known that I, ANDREW B. CAMDEN, a citizen of the United States, residing at Durant, in the county of Bryan and State 5 of Oklahoma, have invented certain new and useful Improvements in Tools for Treating Razor Strops, of which the following is a specification, reference being had to the accompanying drawings.

10 This invention relates to tools for use in the treatment of razor strops.

It is an object of the invention to provide a tool of this character capable of removing all foreign matter from the strop and for 15 dressing the surface of the strop after removal of the foreign matter.

It is a further object of the invention to provide a device of this character wherein one portion thereof not only provides a handle for permitting an adjacent portion of the tool to be used, but wherein said handle portion also provides means for use in the 20 treating operation of the strop.

With these and other objects in view, the 25 invention consists in the improved construction and arrangement of parts to be hereinafter more particularly described, fully claimed and illustrated in the accompanying drawings, in which:—

30 Figure 1 is a perspective view of a razor strop treating device constructed in accordance with an embodiment of the invention and showing the position of the tool when cleaning the strop; and

35 Figure 2 is a perspective view showing the position of the tool when resurfacing the strop.

It is a well known fact that razor strops, especially strops that are in constant use, 40 become filled with grease, steel particles and other foreign matter that greatly impair their efficiency in sharpening razors. The steel particles are usually deposited by the razor and in view of this foreign matter it 45 is impossible to put a smooth cutting edge on the razor. Regardless of the amount of stropping only a wire edge is put upon the razor. When the strop reaches this condition the barber tries almost everything that 50 has been heard of to put his strop back in condition. In view of the fact that no practical device for this purpose has been provided, the barber has to resort to the crude and inefficient means such as lathering the 55 strop, then scrubbing with a towel and

then putting on the working surface with a round, glass bottle. This process is very slow as well as very troublesome and even then does not give the result desired.

In order to overcome this disadvantage 60 and at the same time provide a device which is compact and simple, I have provided a novel form of strop treating tool which does not necessitate any of the crude methods mentioned above, but which may be used to 65 put the strop in condition in a very short time and with little effort or labor on the part of the user.

The tool consists of a body member 5 which is made preferably of a hard, brittle 70 transparent substance, such as glass, this material being preferable over metal in view of the fact that metal would have a tendency to deposit metallic particles on the strop similar to a razor. The body member has 75 its end portion 6 made relatively wide so that the end face 7 thereof is substantially rectangular. The end face 7 is provided with corrugations or teeth 8 which are blunt enough not to scratch or mar the surface of 80 the leather and yet are sufficiently sharp to remove the foreign matter from the pores of the strop. Each tooth is uninterrupted from end to end so as to eliminate sharp projections at the central portion of the face 85 7 and yet provide a scarified face which will readily remove grease, metal particles and like foreign matter from the strop without injury to the strop. The inner faces 9 and 10 of said end portion 6 of the body member 90 are curved inwardly to the central portion 11 of the body member.

The opposite end portion 12 of the body member is considerably smaller than the end portion 6 and is rounded as at 13 to 95 provide a smooth curved surface for use as a surfacing tool. The length of the tool corresponds to the width of the strop. The surfacing tool also provides a handle, as the side portions 14 of the surfacing tool 100 are curved inwardly toward the central portion 11 of the body member, thus providing a hand grip by means of which the operator may grip the device when using the end portion 6 of the body member.

In the use of the device the tool is grasped by the operator, as shown in Figure 1, and applied to the strop A. The tool is then moved longitudinally of the strop so as to 105 permit the teeth 8 to remove the steel par- 110

ticles, grease, and like foreign matter from the strop without injuring the surface of the strop. It is not necessary to apply a liquid or any material whatever to the surface of the strop in order to clean the same, as the glass body member, through the medium of the teeth, is sufficient to remove all foreign matter. After the strop has been treated in this manner the tool is reversed, as shown in Figure 2, so that the handle may be used as a surfacing tool. In view of the round, curved smooth surface of the handle or surfacing tool, it is possible to apply a smooth, dressed and perfect working surface to the strop.

From the foregoing it will be readily seen that this invention provides a novel form of article for use in placing razor strops in perfect condition and wherein the treating operation may be accomplished without the use of liquids or compounds or other implements other than that provided by the tool itself, and all of these features

are possessed by a device that can be formed from a single piece of glass.

25

What is claimed is:—

1. A tool for cleaning and resurfacing razor strops consisting of a body member having one end face thereof corrugated for removing foreign matter from the strop, the opposite end portion of the body member being formed into a handle and a strop surfacing member.

2. A tool for cleaning and resurfacing razor strops consisting of a body member formed from a hard and brittle substance, one end portion of the body member being enlarged, the end face of said enlarged portion having corrugations for cleaning a razor strop, the opposite end portion of the body member being rounded to provide a strop surfacing member.

20 25 30 35 40
In testimony whereof I hereunto affix my signature.

ANDREW B. CAMDEN.
